J. J. WREN

DEVICE FOR WASHING VEHICLES

Filed May 24, 1923

INVENTOR
J. J. WREN
BY Munn & Co.

ATTORNEYS

UNITED STATES PATENT OFFICE.

JOHN J. WREN, OF CHICAGO, ILLINOIS.

DEVICE FOR WASHING VEHICLES.

Application filed May 24, 1923. Serial No. 641,267.

To all whom it may concern:

Be it known that I, JOHN J. WREN, a subject of the King of England, and a resident of Chicago, in the county of Cook and State of Illinois, have invented a new and useful Improvement in Devices for Washing Vehicles, of which the following is a full, clear, and exact description.

My invention relates to improvements in devices for washing vehicles, and it consists in the combinations, constructions, and arrangements herein described and claimed.

An object of my invention is to provide a simple device by means of which mud, dust, etc., may be washed off from vehicles such as automobiles, and the like, in a most effective manner.

A further object of my invention is to provide a simple device in which a stream of water is forced by air pressure from a nozzle at high velocity, air being mixed with the stream so as to break the stream up into a series of intermittent jets which more effectively remove mud and dust than a mere stream of water under high pressure.

A further object of my invention is to provide a device which is of relatively compact form, thereby enabling the device to be manipulated into small spaces, as for instance, between the spokes of an automobile wheel.

A further object of my invention is to provide a device of the type described that is adapted to mix a cleaning fluid, such as kerosene, with the water.

Other objects and advantages will appear in the following specification, and the novel features of the invention will be particularly pointed out in the appended claim.

My invention is illustrated in the accompanying drawing forming part of this application, in which—

Figure 1 is a side elevation of the device, portions thereof being shown in section,

Figure 2 is a section along the line 2—2 of Figure 1, and

Figure 3 is a section of another portion of the device.

In carrying out my invention, I provide a header or mixing chamber A having a water inlet B communicating with a water pipe D. In the present instance I have shown this pipe as being integral with the header A. The pipe D is connected with a hose section F which leads to any suitable supply of water, not shown.

The header is provided with a discharge opening G, and on the opposite side, there is an inlet H for air. An air inlet pipe K, integral with the header A and the pipe D, is provided with a valve L, by means of which the air can be shut off entirely or admitted at will. The free end of the pipe K is connected with a flexible hose P leading to some suitable supply of compressed air, such as the supply hose found in all public garages for transmitting air for the inflation of tires.

I have found that water mixed with a cleaning fluid such as kerosene will more effectively clean than if water alone were used. To this end I provide a nipple Q that is removably disposed in an opening R in the header A. A flexible pipe S is secured to the nipple Q. The pipe S is in communication with a cleaning fluid such as kerosene or the like. The rushing of the air and water past the inner end of the nipple R and out through the outlet G creates a suction in the nipple and entrains the kerosene, the kerosene being thoroughly mixed with the water before the water strikes the surface to be cleaned. This suction is sufficient to draw the kerosene from the receptacle in which it is contained.

A hand grip or covering T is secured to the casting by any means such as bolts U. The casting has the header A, the pipe D, and the pipe K, fashioned therein, and can be handled as a single unit. The hand grip or covering T is made out of any material desired, preferably of some material that is a non-conductor of heat. If the handle T, is a non-conductor of heat, the device can be readily used when it is desired to have the pipe D carry hot water, or any other kind of hot or cold fluid.

From the foregoing description of the various parts of the device the operation thereof may be readily understood. A device constructed as above described provides a very efficient means for cleaning cars. The water is first turned on at the source of supply and air is admitted by turning the valve L. The admission of air accomplishes two important results. One is that it increases the pressure so that the resulting stream from the outlet G is of high velocity. The second is that the air mingles with the water and breaks up the stream into a series of intermittent jets. Of course these jets appear as a solid stream, since the water is

traveling at a high velocity. I have found that with a given amount of water a car can be more effectively cleaned with my device that employs an air jet, than with one that is not provided with an air jet, and I attribute this fact to the mingling of the air with the water, as well as to the high pressure imparted to the stream.

The kerosene or other cleaning fluid when 10 mixed with water provides a very efficient cleaning fluid. In case the operator only desires to use the water, the nipple Q is removed and a set screw V is disposed in the threaded opening R. It will be noted 15 from Figure 1, that a fin W is disposed in the head A and is positioned between the pipes D and H to prevent the water from passing into the pipe H.

The device is especially effective where the 20 only water pressure that is available is low. Then the full force of the air may be admitted to the header, thus imparting the necessary velocity to the water to cause the dislodgment of the mud, dirt, or grease,

The device may be used with hot water 25 as well as cold, and is especially effective in removing grease without the use of soap.

I claim:

A device for washing cars, comprising a casting having a mixing chamber with an outlet nozzle, said casting having a water inlet and an air inlet to said chamber, the end of the air inlet comprising a pipe that is disposed within said chamber and bent so as to direct the stream of air toward the water that is being conveyed into the chamber from the water inlet, the inner end of the water inlet comprising a partition separating the rear portion of the mixing chamber from the water inlet and disposed adjacent to the air pipe, a fluid inlet disposed adjacent to said pipe, and in converging relation thereto whereby the air flowing from said pipe will entrain the fluid from said fluid inlet, and a valve for controlling the flow of air through said air inlet.

JOHN J. WREN.
